UNITED STATES PATENT OFFICE.

WILLIAM ILE, OF JACKSON, MICHIGAN, ASSIGNOR TO REYNOLDS SPRING COMPANY,
OF JACKSON, MICHIGAN, A CORPORATION OF DELAWARE.

PUSH-THROUGH SWITCH.

Application filed August 18, 1925. Serial No. 50,924.

The invention relates to a push through switch.

The object of the present invention is to improve the construction of electric switches and to provide a simple, practical and efficient push through switch of strong, durable and comparatively inexpensive construction which will present a neat and attractive appearance and which will be of a minimum size.

Another object of the invention is to provide a push through switch of this character in which the casing may be molded in two sections of bakelite or similar insulating material and in which a minimum amount of such material will be employed and which will afford a firm solid support for the mechanism and electrical connections of the push through switch.

With these and other objects in view, the invention consists in the construction and novel combination and arrangement of parts hereinafter fully described, illustrated in the accompanying drawings and pointed out in the claims hereto appended, it being understood that various changes in the form, proportion and minor details of construction, within the scope of the claims, may be resorted to without departing from the spirit or sacrificing any of the advantages of the invention.

In the drawings:

Figure 1 is a side elevation of a push through switch constructed in accordance with this invention.

Fig. 2 is a similar view looking at the push through switch at right angles to Fig. 1.

Fig. 3 is a central longitudinal sectional view of the push through switch.

Fig. 4 is a similar view taken at right angles to Fig. 3.

Fig. 5 is a central transverse sectional view of the device.

Fig. 6 is an elevation of the shell section of the casing showing the inner face of the same.

Fig. 7 is a side elevation of the push slide.

Fig. 8 is a side view of the oblong bracket or support.

Fig. 9 is an end view of the same.

In the accompanying drawings in which is illustrated the preferred embodiment of the invention, the push through switch is pro-

vided with a substantially cylindrical casing 55 1 of bakelite or other suitable material molded in two approximately semi-cylindrical sections 3 and 4, the section 3 being substantially solid and constituting a firm support for the switch mechanism and electrical 60 connections and the section 4 consisting of a shell or hollow semi-cylindrical member. The sections are provided at their ends with central semi-circular recesses 5 and 6 forming central openings in the ends of the 65 cylindrical casing when the sections are assembled and the said casing is closed at the sides and ends except for the end openings and side recesses 7 formed in the opposite edges of the section 3 centrally thereof for the passage of push buttons 8 of a push slide 9 of the snap switch mechanism hereinafter described. The side and end edges of the section 4 are adapted to fit against 70 corresponding edges formed by opposite 75 marginal flanges 10 of the section 3.

The marginal flange 10 of the section 3 forms a shallow compartment or chamber and the section 3 is provided at its ends at one side of the center with substantially 80 rectangular recesses 11 in which is secured attaching plates 12 of stationary switch terminals 13 spaced apart and adapted to be engaged by an oscillatory switch member 14 as clearly illustrated in Fig. 4 of the drawings. The stationary switch terminals 13 consist of arms extending from the attaching plates 12 at substantially right angles to the same and having their outer terminals 15 inwardly offset by angular bends and provided with contact lugs 16 extending from the arms at one side edge thereof and arranged at right angles to the plane of the arms. The contact lugs 16 of the stationary 90 switch terminals form abutments for the movable switch member and are engaged by the same at the limit of the movement of the said member in one direction. The contact lugs 16 are set at an angle or inclination 95 and present flat faces to the movable switch member. The attaching plate 12 is substantially rectangular and fits in the rectangular recess 11 and is secured therein by a combined binding and attachment screw 17 100 piercing the attaching plate and engaging a 105 suitable threaded opening in the section 3. The threaded openings for the binding screws may be formed by metallic bushings

embedded in the bakelite when the sections are molded as will be readily understood. The terminals of the wire in which the switch is placed are brought through the end 5 openings of the casing and are secured in the usual manner by the binding screws 17 and when the movable switch member is in contact with the stationary switch terminals a current is permitted to flow through the 10 switch and when the movable switch member is carried to its opposite position the current will be interrupted as will be readily understood.

The snap switch mechanism comprises in 15 its construction the movable switch member, a substantially rectangular bracket or support 18 composed of spaced parallel sides and parallel ends all formed of a single piece of metal the terminals of the metal 20 being spaced apart at one of the corners of the rectangular bracket or support as clearly illustrated in Fig. 4 of the drawings so as to give resiliency to the bracket or support. By virtue of this resiliency, that is, one side 25 of the bracket or support being compressible toward and away from the opposite side, the support may maintain itself firmly in position by reason of its snug fit between the walls *a* and *b* (Fig. 4). This support or bracket 30 is formed by bending a plate or strip of sheet metal at right angles at intervals to form side and end walls and the sides of the support are compressed in introducing the same in position between the walls *a* and 35 *b* and when pressure is removed from the sides of the oblong support the resiliency or spring action of the sides will firmly hold the snap switch mechanism in position. To positively fasten the support to the section 40 3 the support is provided with the lug 19 which is perforated for the reception of a suitable fastening device 21. The rectangular bracket is arranged centrally of the section 3 and extends across the same and fits 45 between the marginal flanges 10 thereof and it is provided at one side with an attaching lug 19 fitted in a recess 20 in the section 3 and secured to the latter by a screw 21 piercing the attaching lug and engaging a suitable 50 threaded opening in the said section 3 of the casing. The threads may be formed by a metallic bushing or any other desired manner. The sides of the support 18 are provided with inwardly tapered recesses 22 55 having oppositely inclined side walls and forming open bearings 23 at the apex. The oppositely inclined walls of the recesses 22 form stops for limiting the swing of the movable switch member which consists of 60 a yoke having spaced parallel sides and a connecting cross bar which projects laterally beyond the outer edges of the sides to form contact terminals 24 which engage the contact lugs of the stationary switch terminals. The sides of the movable switch mem-

ber are provided at their inner ends with laterally extending pivot studs 25 which are arranged in the open bearings 23 of the support and the outer portions 26 of the sides of the movable switch member are extended 70 laterally or widened to project into the recesses 22 for engaging the side walls of the same for limiting the swing of the movable switch member.

The oblong bracket besides forming a 75 support for the oscillatory switch member also serves as a guide for the push slide 9 which consists of a substantially rectangular body portion 27 arranged between the sides of the support and provided with arms 80 28 and 29 arranged in pairs and having tapering recesses at their inner opposed edges. The inner edges of the outer portions of the arms converge toward their outer ends as clearly shown at 29 in Fig. 7 and they are adapted to fit against the sides of the movable switch member and positively move the same into contact with the stationary switch terminals and also to the limit of the movement of the switch member in the opposite 85 direction. The cross bar of the movable switch member is provided with an eye or opening 30 into which is linked the outer end 31 of a coiled spring 32 and the inner end 33 of the coiled spring is linked into an eye or opening 34 of the push slide. The eye or opening 34 of the push slide is preferably formed by an opening in a central longitudinal rib 35 formed integral with the body portion of the push slide. When the slide is moved from one side of the casing to the other the spring is carried beyond a central position and the movable switch member is also engaged by the push slide and the spring is carried beyond a central position and the movable switch is carried into and out of contact with the stationary switch terminals with a snap action and is positively maintained in both positions by engagement of the push slide and the spring action. The tension of the spring 90 will maintain both the slide and the movable switch member in either of their positions. The slide is provided at its ends with integral shanks 36 arranged in longitudinal 95 alignment and embedded in the push buttons 8 which are molded of bakelite or other suitable insulating material but any other suitable form of insulated push button may be provided for actuating the slide. The ends of the oblong bracket are provided with openings 41 for the passage of the push buttons and the spacing of the terminals of the piece of metal forming the oblong support or bracket will permit the 100 ready assembling of the parts.

The substantially solid section 3 is provided with transverse openings 37 for the reception of screws 38 which engage threaded openings 39 in lugs or enlargements 105 110 115 120 125 130

formed integral with the shell section 4 as clearly shown in Fig. 3 of the drawings. The outer portions of the openings 37 are counterbored as shown at 40 to receive the heads of the transverse screws 38 which securely fasten the sections of the casing in assembled relation. All of the parts of the snap switch mechanism and the electrical connections are mounted on the solid section 10 which provides a firm and secure support for such parts and the shell section serves as a cap for the solid section.

What is claimed is:

1. An electric switch of the class described including snap switch mechanism comprising a support having side and end walls, the side walls having aligned recesses opening through the upper edges of the sides, the ends of the support having aligned openings, a slide guided in the support and having terminal push buttons slidable through said end openings of the support, said slide having a pair of arms at each end, a movable switch member fulcrumed in said recesses and arranged to be engaged and positively actuated by the pairs of arms of said slide, and a spring connection between the slide and the movable switch member against the action of which the pairs of arms of the slide operate the switch member.

2. An electric switch of the class described including snap switch mechanism comprising an oblong support having side and end walls, the side walls being provided with V-shaped recesses and the end walls having aligned openings, a slide guided in the support and having terminal push buttons slidable through said end openings of the support, said slide being also provided at opposite sides with spaced arms located at the said V-shaped recesses, a movable switch member consisting of a swinging yoke having its sides fulcrumed in the V-shaped recesses and arranged to be engaged and positively actuated by the arms of the slide, and a spring connection between the slide and the movable switch member.

3. An electric switch of the class described including snap switch mechanism comprising spaced stationary switch terminals, a support having side and end walls, the side walls being provided with V-shaped recesses and the end walls having aligned openings, a slide guided in the support and having terminal push buttons slidable through the said end openings of the support, said slide being also provided at opposite ends with pairs of arms, the inner edges of the outer portions of one pair of arms converging toward the outer portions of the inner edges of the other pair of arms, a movable switch member fulcrumed in said V-shaped recesses and arranged to be engaged and positively actuated by the converging outer portions of the inner edges of the pairs of arms of said slide,

and a spring connection between the slide and the movable switch member against the action of which the pairs of arms of the slide operate the switch member.

4. An electric switch of the class described including spaced stationary switch terminals, a substantially oblong support having side and end walls, the side walls being provided with V-shaped recesses and the end walls having aligned V-shaped openings, a slide guided in the support and having terminal push buttons slidable through said V-shaped end openings of the support, said slide being also provided at opposite sides with spaced arms located adjacent the said V-shaped recesses, a movable switch member consisting of a swinging yoke fulcrumed in the V-shaped recesses and arranged to be engaged and positively actuated by the arms of the slide, the slide having a central longitudinal rib provided with an opening, and a spring having connection at one end with the opening in said rib and at its other end connected with the switch member.

5. A push through switch including an insulating casing having a recess therein, spaced stationary switch terminals mounted within the casing, a substantially oblong support having side and end walls mounted in the casing, the side walls being provided with V-shaped recesses forming bearings and the end walls having aligned openings, the support having a laterally projecting lug fitting in said recess of the casing, means piercing the lug to secure the support to the casing, a slide guided in the support and having terminal push buttons slidable through the said end openings of the support and through the said casing, said slide being also provided with a recess and at the ends of the recess being provided with pairs of spaced arms, a swinging switch member having its sides fulcrumed in the V-shaped recesses of the support and arranged to be engaged and positively actuated by the arms of the slide, and a spring connected at one end in the opening of said rib and at its other end having connection with the swinging switch member.

6. A push through switch including a casing composed of sections formed of insulating material, means for securing the sections together, spaced stationary switch terminals mounted within the casing, a substantially oblong support having side and end walls mounted in the casing, one of the side walls at one corner of the support terminating short of the end wall, the side walls of the support being provided with V-shaped recesses forming open bearings and the end walls having aligned openings, a slide guided in the support and having terminal push buttons slidable through said end openings of the support and also through the side walls of the casing, said slide being also pro-

vided at opposite sides with spaced arms located adjacent the said V-shaped recesses, a movable switch member having projections disposed in the V-shaped recesses and arranged to be engaged and positively actuated by the arms of the slide, and a spring connection between the slide and the movable switch member.

7. An electric switch of the class described 10 including a snap switch mechanism comprising a sectional casing with one of the sections having spaced walls, an oblong support composed of sheet metal bent to provide side and end walls, the side walls being formed 15 integral with one of the end walls and one of the side walls being unconnected with and terminating short of the other end wall whereby to give resiliency to the support to

maintain it firmly in position between said walls of one of the sections of the casing, 20 means to positively secure the support in the casing, a slide guided in said support and having terminal push buttons slidable through the ends of the support and the 25 casing sections, said slide being also provided with spaced arms, a movable switch member fulcrumed to said support and arranged to be engaged and positively actuated by the said arms of said slide, and a spring 30 action between the slide and movable switch member against the action of which the arms of the slide operate the switch member.

In testimony whereof I have hereunto set my hand.

WILLIAM ILE.
